CLAIM

The ornamental design for a candle warmer lamp, as shown and described.

DESCRIPTION

FIG. 1 is a perspective view of a candle warmer lamp showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and

FIG. 8 is a bottom plan view thereof; and,

FIG. 9 is a partial enlarged view of FIG. 1 thereof.

The broken lines shown in the drawings illustrate portions of the candle warmer lamp that form no part of the claimed design. The dot dash broken lines in FIGS. 1 and 9 delineate areas of the figures shown enlarged and form no part of the claimed design.

1 Claim, 9 Drawing Sheets
